UNITED STATES PATENT OFFICE.

LEONIDAS G. WOOLLEY, OF LIMA, OHIO, ASSIGNOR TO JOHN C. RILEY, OF LIMA, OHIO.

CIRCUIT-OPERATING DEVICE.

No. 857,708.

Specification of Letters Patent.

Patented June 25, 1907.

Application filed August 31, 1906. Serial No. 332,798.

To all whom it may concern:

Be it known that I, LEONIDAS G. WOOLLEY, a citizen of the United States, residing at Lima, in the county of Allen and State of Ohio, have invented certain new and useful Improvements in Circuit-Operating Devices; and I do hereby declare the following to be a full, clear, and exact description of the invention, such as will enable others skilled in the art to which it appertains to make and use the same.

The object of this invention is to provide an improved circuit operating device especially adapted for use in connection with fire alarm systems, of simple and economical construction and adapted to be operated without the use of cells.

The invention consists in the construction shown, described and pointed out in the appended claims, the invention not being confined to the precise forms of the parts illustrated.

In the accompanying drawings—Figure 1 is a view of the mechanism in side elevation; Fig. 2 is a top plan view; and Fig. 3 is a detail illustrating the device for releasing the escapement lever.

In the views 1 designates the drum of a motor and containing a suitable power spring for driving it in the direction indicated by the arrow thereon Fig. 1. One end of the drum is furnished with a head 2 having a smooth rim except where it is provided with a notch 3. The other end is furnished with a spur gear 4. Arranged parallel to the drum are three shafts 5, 6, and 7 geared together by a suitable train. On the shaft 5 is a signal or number wheel 8 provided with inclined teeth spaced to give a signal, as hereinafter described, when the drum is rotated. The signal wheel 8 is rotated in the direction indicated by the arrow thereon Fig. 1.

Pivoted at 9^a is a horizontal lever 9 carrying a block 9^b having an inclined lower edge to ride on the rim and teeth of the wheel 8. The lever 9 is held downward by means of a spring 10. Connected hingedly with the free end of the lever 9 is a vertical bar 11 having rack teeth at its lower end.

12 is a permanent magnet and 13 is a coiled armature working between the poles of said magnet.

14 is the shaft of the coiled armature, and

this shaft is provided with a spur gear 14^a that is engaged by the rack teeth of the bar 11. 55

When the rack bar is constructed to operate the wheel 14^a on the up-stroke of that bar the signal apparatus should be made incapable of operation by the weaker electro-motive force generated by the slower motion of the 60 coiled armature produced by said up-stroke.

The shaft 7 has a star wheel 7^a that is engaged by an ordinary escapement 15 affixed to the shaft of which is an arm 15^a carrying a lateral pin 15^b. 65

16 is a lever pivoted at 16^a and having a handle at one end and a dog 16^b at the other arranged to engage the notch 3 in the head 2 of the drum. The lever 16 also has a stop 16^c that, when the dog 16^b is engaged with the 70 notch 3, lies in the path of the pin 15^b and prevents vibration of the escapement arm 15^a and therefore the operation of the escapement. The lever 16 is held with its dogged end down by means of a spring 17. 75

Assuming that the power spring for operating the drum 1 has been duly wound and it is desired to send a signal, the operation is as follows: Upon pulling down the handled end of the lever 16 and lifting the dog 16^b out of the notch 3 the escapement is permitted to operate as is usual with escapements. The signal wheel 8 is rotated and the lever 9 intermittently oscillated by the teeth of said wheel 8. Because of the construction of the 85 teeth of the wheel 8 and the rider block 9^b the downward movement of the lever 9 and consequently of the bar 11 is quick and hence imparts a quick rotation to the shaft of the armature coil 13 thereby generating an electrical impulse in said coil. This impulse is conveyed by suitable conductors 13^a to a gong or other signaling device. In the instance shown the wheel 8 is provided with seven teeth arranged to signal the number 95 232. The dog, when lifted out of the notch 3 to send a signal and after the drum has moved a little, may be allowed to ride on the smooth rim of the head 2, and to automatically drop into said notch upon a complete 100 revolution of said head. The circumference of the gear 4 may be to the small gear it engages as five is to one, in which case the wheel 8 will be revolved five times in one revolution of the drum and the same signal given that 105 number of times.

What I claim and desire to secure by Letters Patent is:

1. In a circuit-operating device, the combination of a motor, a signal wheel driven thereby, an electromagnetic generator, and means for operating said generator by the signal wheel.
2. In a circuit-operating device, the combination of a motor, a toothed signal wheel driven thereby, a lever carrying a rack bar said lever being actuated by said toothed wheel, an electromagnetic generator including a coiled armature having a shaft, and a pinion on said shaft engaged by said rack bar.
3. In a circuit-operating device, the combination of a motor, a signal wheel driven thereby, an electromagnetic generator, means for operating said generator by the signal wheel, an escapement for controlling the operation of the motor, and means for automatically stopping the operation of the escapement.
4. In a circuit-operating device, the combination of a motor, a signal wheel driven thereby, an electromagnetic generator, means for operating said generator by the signal wheel, an escapement for controlling the operation of the motor, means for manually releasing said escapement and automatically stopping its operation.
5. In a circuit-operating device, the combination of a motor, a signal wheel driven thereby, an electromagnetic generator including a coiled armature, and means between the generator and the signal wheel adapted to give intermittently quick movements to the armature of the generator.

In testimony whereof I affix my signature, in presence of two witnesses.

LEONIDAS G. WOOLLEY.
